UNITED STATES PATENT OFFICE.

GEORGE LANDER JACQUES, OF NEILLSVILLE, WISCONSIN.

ROTARY ENGINE AND PUMP.

1,307,631.

Specification of Letters Patent. Patented June 24, 1919.

Application filed December 27, 1917. Serial No. 209,072.

To all whom it may concern:

Be it known that I, GEORGE LANDER JACQUES, a citizen of the United States, residing at the city of Neillsville, in the county 5 of Clark and State of Wisconsin, have invented a new and useful Rotary Engine and Pump, of which the following is a specification.

My invention relates to improvements in 10 rotary engines and rotary pumps. The objects of my improvements are, first, to provide a rotary engine operated by steam pressure instead of the striking force of escaping steam; second, to provide a rotary pump that 15 will elevate the fluid being pumped by direct pressure; third, to provide successive cylinders forming a compound engine to use the expansive force of the exhausted steam from each preceding cylinder; fourth, to provide 20 a rotary piston with abutment pistons hinged thereto that will close against said rotary piston in the part of the revolution thereof bringing its outer surface nearest to the inner surface of the cylinder and that will open 25 against the inner surface of the cylinder in other parts of the revolution of said rotary piston; fifth, to provide guides and cam to open said abutment pistons; sixth, to provide glands and stuffing boxes for the operation of 30 said guides without leakage; seventh, to provide a proper outer casing or cylinder within which said rotary piston and abutment pistons operate; eighth, to provide rings on 35 said rotary piston to prevent leakage; ninth, to provide rings or segments on the upper and lower edges of said abutment pistons to prevent leakage; tenth, to provide a bar or segment on the inner surface of the cylinder at the point where the outer surface of the 40 rotary piston comes nearest to it to prevent leakage; eleventh, to provide proper packing in the hinges of the abutment pistons to prevent leakage through said hinges.

I attain these objects by the mechanism 45 illustrated in the accompanying drawings, in which—

Figure 1 is a side elevation of the device arranged as a triple cylinder engine; Fig. 2 is a detailed view of the cylinder (with the 50 cover removed) and the rotary piston, abutment pistons, guides and cam rollers operating in said cylinder; Fig. 3 is a sectional view of the device; Fig. 4 is a plan view of the bottom cover and exhaust chamber; Fig. 5 is a sectional view through top cover at line 2; Fig. 6 is a plan view of cover and in-

take chamber; Fig. 7 is a section of the rotary piston with detail of abutment piston, guide and cam roller; Fig. 8 is a segment of 60 the rim of the cylinder with details of steam bar in said rim; Fig. 9 is a sectional view through bottom cover at line 3.

Similar letters refer to similar parts throughout the several views.

Referring to the drawing Fig. 2, 10 designates the rotary piston which is keyed to the shaft 30 which is loosely journaled in the lugs 11 and 12. See Fig. 3. The wings or vanes 13 are hinged to the piston 10 at 14, said hinge being provided with packing 15 (see Fig. 7) to prevent leakage through the hinge. The piston 10 is provided with piston rings 16 on its outer edge also the piston ring 17 on its inner surface, said piston rings being forced out to the inner surface 75 of the top and bottom cover by the pressure through the port holes 8.

The wings or vanes 13 are provided with the packing segments 19, said segments are forced out to the top and bottom covers by 80 pressure through the port holes 20. The guides 21 are fastened to the wings or vanes 13 by a pin and flange 22 securely fastened thereto and said guides run through the piston 10, the latter having a gland and stuffing 85 box 23 for each guide 21. A cam roller 24 is mounted in the forked end of each guide 21 and travels against the cam 25 which is a part of the bottom cover 26. The steam bar 27 is bedded into the inner surface of the 90 casing 26 and forced against the wings or vanes 13 to prevent any leakage toward the exhaust port 28, said bar being forced toward the abutment pistons by pressure entering through port holes 29 in the casing 95 33 as shown in Fig. 8.

Referring to Fig. 3, a cross sectional view showing the relative position of the piston, wings or vanes, guides and piston rings inside the cylinder, the piston 10 is keyed to the shaft 30 by the key 31 said shaft being loosely journaled through the hub 11 of the top cover 32 and also loosely journaled through the hub 12 of the bottom cover 26 said covers and the cylinder casing 33 being held in position by the bolts 34, the lower bolt 35 is also extended through portions 36 of the bases of the main frames or supports 37 and *cc*.

The frame bearings 38 for the shaft 30 are 110 located at the upper ends of the frames 37. The piston rings 17 are forced by the pres-

sure through the port holes 18 against the annular shoulders 39 on the inner faces of top cover 32 and bottom cover 26. The wings or vanes 13 are hinged to the piston as before described so that their rings 19 engage the inner faces of the top cover 32 and bottom cover 26.

Referring to Fig. 8 I have shown a section through a portion of casing 33 illustrating 10 steam bar 17 and ports 29 on the inside face of the said casing, the dotted lines indicating pockets back of the bar to allow steam or fluid to enter and force the bar against the wings or vanes 13.

15 Referring to Fig. 1 I have shown the complete engine arranged as a triple cylinder engine, the pulley 40 being mounted on the extreme end of the shaft 30 carried in the main bearings 38 of frames 37. In operation 20 steam enters through a valve 41 and passes into the intake chamber 42 where it is distributed into two chambers simultaneously between wings or vanes of the first cylinder, making its way through to the exhaust 25 chamber 43 and thence through the flanged coupling 44 to intake chamber 45 of the second cylinder, and so on through the cylinders 46, 47 and 48, and is finally exhausted through the exhaust pipe 49. The cylinders 30 are provided with drain cocks 50 to drain the condensed water out of the cylinders and prevent pounding.

My invention may it will thus be seen, be used as a single cylinder steam engine using 35 only one cylinder or it may be used as a compound steam engine using as many successive cylinders as may be desired.

In my invention the rotary engine may be driven either by steam or any explosive gas.

40 It is also obvious that my invention may be used as a rotary pump by using only one cylinder, applying the power to the shaft 30 reversing the motion from what it would be when used as a steam engine.

45 In operation each cylinder receives steam through the intake chamber of its cover 32 between the steam bar 27 as seen in Fig. 2 and the next adjacent wing or vane 13 beyond the steam bar. The wing or vane 13 in 50 question has just passed the steam bar and has already been shifted on its hinge 14 to hold its outer free end in engagement with the inner surface of casing 33 by the cam 25 and guide 21, so that the steam is thus free 55 to expand against said wing or vane between the same and the stationary steam bar 27. Thus if used as an engine the steam rotates the piston 10 and if used as a pump the fluid to be pumped is carried in the same way by 60 positive rotation of the piston 10.

During this operation leakage will be reduced to minimum by virtue of the rings and ring segments of the piston 10, and wings or vanes 13 and the piston boxes for 65 the guides 21, which are the movable parts

subjected to the influence of the steam, thus reducing friction, preventing waste, and consequently preserving the engine against loss of power and in condition for greatest efficiency at all times.

To the above end the particular oval shape of the cylinder co-operates, of course, with the similar shape of the cam 25 constituted by a flange upon the inner portion of the cover 26, as well as the particular eccentric 75 disposal of the piston 10 within the casing 33 and between the covers 26 and 32.

I claim:

1. In a rotary device of the character described, the combination of a rotary circular piston, a shaft upon which said piston is secured, supports having bearings for said shaft, an oval casing within which said piston is eccentrically disposed, covers secured to and closing the sides of said casing, portions of which covers and the casing are secured to said bearing supports to hold the same stationary, wings or vanes hinged to the outer surface of the piston to swing outwardly into engagement with the casing, said piston and said wings or vanes having fluid tight engagement with the inner surfaces of the said covers, curved guides extending inwardly from the said wings or vanes and movable through the piston, and an abutment member carried by the casing with which the several wings or vanes engage, one of said covers having an inner flange forming a cam within the piston and engaged by the inner free ends of the said 90 wing guides.

2. In a rotary device of the character described, the combination of a rotary piston, a shaft on which said piston is secured, supports having bearings for the said shaft, a 105 casing within which said piston is eccentrically disposed, covers secured to and closing the sides of the said casing, wings or vanes hinged to the piston for swinging outwardly into engagement with the casing, guide 110 members connected at their outer ends to the said wings or vanes, and projecting inwardly through the piston, and a steam bar carried by the casing for engagement by the several wings or vanes, one of said covers 115 having an inner flange forming a cam within the piston and engaged by the inner free ends of the said guides.

3. In a rotary device of the character described, the combination of a rotary piston, 120 a shaft on which said piston is secured, supports having bearings for the said shaft, a casing within which said piston is eccentrically disposed, covers secured to and closing the sides of the said casing, wings or 125 vanes hinged to the piston for swinging outwardly into engagement with the casing, guide members connected at their outer ends to the said wings or vanes and projecting inwardly through the piston, and a steam bar 130

carried by the casing and having a fluid controlled movement toward and away from the piston for engagement by the several wings or vanes, said piston and the said wings or vanes, said piston and the said wings or vanes having movable fluid tight engagement with the inner surfaces of the said covers, one of said covers having an inner flange forming a cam within the piston and engaged by the inner free ends of the 10 said guides.

4. In a rotary device of the character described, the combination of a rotary piston, a shaft on which said piston is secured, supports having bearings for the said shaft, a 15 casing within which said piston is eccentrically disposed, covers secured to and closing the sides of the said casing, wings or vanes hinged to the piston for swinging outwardly into engagement with the casing, guide members connected at their outer ends to the 20 said wings or vanes and projecting inwardly through the piston, a steam bar set into the inner surface of the casing, said casing having a pocket at the rear of the said steam 25 bar, and a groove opening at one side of the bar and communicating with said pocket to admit fluid pressure behind the steam bar and press the same toward the piston for engagement by the several wings or vanes 30 and one of said covers having an inner portion forming a cam within the piston and engaged by the inner free ends of the said guides.

5. In a rotary device of the character described, the combination of a rotary piston, a shaft on which said piston is secured, supports having bearings for the said shaft, a 35 casing within which said piston is eccentrically disposed, covers secured to and closing the sides of the said casing, wings or vanes hinged to the piston for swinging outwardly into engagement with the casing,

guide members connected at their outer ends to the said wings or vanes, and projecting inwardly through the piston, a steam bar 45 carried by the casing for engagement by the several wings or vanes, one of said covers having an inner flange forming a cam within the piston and engaged by the inner free ends of the said guides, said wings or vanes 50 having grooves in their side edges, and ports in their side faces communicating with said grooves, packing strips extending within said grooves and held against the inner surfaces of said covers by the pressure of fluid 55 in the grooves through said ports.

6. In a rotary device of the character described, the combination of a rotary piston, a shaft on which said piston is secured, supports having bearings for the said shaft, a 60 casing within which said piston is eccentrically disposed, covers secured to and closing the sides of the said casing, wings or vanes hinged to the piston for swinging outwardly into engagement with the casing, 65 guide members connected at their outer ends to the said wings or vanes, and projecting inwardly through the piston, a steam bar carried by the casing for engagement by the several wings or vanes, one of said covers 70 having an inner flange forming a cam within the piston and engaged by the inner free ends of the said guides, said piston having annular side grooves, and ports in the outer surface thereof communicating with said 75 grooves, and packing rings disposed in the grooves and held outwardly against the inner surfaces of said covers by the pressure of fluid in the grooves through the said ports.
